or leatherette articles have polished surfaces. The invention is particularly applicable to the polishing of small articles such as buttons, beads, small pieces of metal, and the like. They may be required to have a polished surface, or to be cleaned and polished, or to be given a special finish.

UNITED STATES PATENT OFFICE

2,494,733

PROCESS FOR POLISHING ARTICLES AND A DEVICE FOR USE THEREIN

Ernest George Whitehead, Wolverhampton, England, assignor to The Wolverhampton Die-Casting Company Limited, Wolverhampton, England

Application June 25, 1946, Serial No. 679,226

In Great Britain March 15, 1946

4 Claims. (Cl. 51-7)

1

The invention has for its object to provide an improved process by which articles may be automatically and efficiently polished, and to provide an improved device for use therein. Heretofore the polishing of small articles has usually been effected by holding such articles against a fabric bob or mop rotated at a high speed and supplied with abrasive polishing material.

According to this invention the articles are placed within a drum containing small solid pieces of material and polishing material, the articles being mounted on a carrier within the drum, relative rotation being provided between the drum and the carrier whereby the said small solid pieces of material are caused to rub against the articles and, together with the polishing material, effect the polishing thereof.

The polishing material may be in the form of powder or compound, or the said small solid pieces may have polishing material impregnated in them.

The small solid pieces of material may be composed of felt or other fabric, or of rubber, leather, papier-mâché or any other resilient material, or of shot or a combination of any of these. The inner periphery of the drum may be lined with resilient material, which may be some of the above named solid pieces of material held against the inner periphery by centrifugal force if the drum is rotated. The said inner periphery may, however, be permanently lined with resilient material, such as rubber, leather or fabric.

An example of the invention is described with reference to the accompanying drawings, of which:

Figure 1 is a side elevation of the polishing device.

Figure 2 is a front end view thereof.

Figure 3 is a vertical section taken on the line 3, 3, of Figure 1 and looking in the direction of the arrow of that figure.

Figure 4 is a sectional plan view, the section being taken on the line 4, 4, of Figure 1.

Figure 5 is a detail in plan showing a simple means for driving the drum in opposite directions.

In these drawings, 10 indicates a main casting affording support to two bearings 11, 11, and a horizontal supporting bar 12, see Figure 1. Journalled in the bearings 11, 11, is a shaft 13 on which are keyed a belt pulley 14 and a hollow drum 15 which has a closed rear wall 16. Clamped on the bar 12 is an upwardly extending bracket 17 having at its upper end a boss 18 in which is se-

2

cured, by set screws 19, an arbor 20 which extends rearwardly into the drum 15 and is concentric therewith. On the rear end of the arbor 20 is keyed a circular carrier 21 which is located in the drum and has screwed into its periphery a set of radially extending arms 22.

Secured to the arms 22, by screws 23, are jigs 23a which hold the articles 24 required to be polished.

10 The drum 15 has a flange 25 at its forward end and behind the flange are pairs of lugs 26 to which are pivoted eye bolts 27 adapted to pass through notches 28 in the flange 25 and through corresponding notches in the periphery of a cover plate 29, this latter being secured against the flange 25 by wing nuts 30 screwed on the eye bolts 27.

15 The bracket 17 is clamped on the bar 12 by a sunk-headed screw 31 and a hand clamping screw 32, both of which pass through clearance holes in a strap 33 and screw into tapped holes in the bracket 17.

20 In order to remove the carrier 21, with its arms 22, from the drum 15, the bolts 27 are disengaged from the cover plate and the hand screw 32 is slackened back. This permits of the bracket 17 being slid back along the bar 12 bringing with it the arbor 20, the cover plate 29 and the carrier 21 with its arms 22. The articles 24 can then be detached and replaced. The drum is partially filled with small solid pieces of material 34, together with abrasive material.

25 When the articles have been fitted to the arms on the carrier, the latter inserted in the drum and the cover plate secured in position, the drum is driven at speed by applying power to the belt pulley 14. The rotation of the drum, by imparting centrifugal force to the small solid pieces of material, causes a proportion of them to pack on the inner surface of the drum 15 and form a resilient layer which sweeps over the outer and side surfaces of the articles; or causes said small pieces to come in close proximity thereto; and the rotation causes other pieces of material passing 30 between the said layer and the articles to rub against the articles. In either case the small solid pieces of material, and especially the abrasive material thereon, rapidly effect the polishing of the said outer surfaces and sides of the articles. 35 The inner sides and the shanks of the articles are also polished by other of the small solid pieces of material revolving in orbits nearer to the axis of the drum.

40 It is beneficial to reverse the direction of rotation intermittently to equalise the polishing effect.

A simple mechanism for effecting reversal of the rotation may comprise a motor-driven shaft 40 having a pulley 41 keyed thereto and driving a countershaft 42 by a belt 43 and a pair of pulleys 44, and 45. Crossing the belt 43 as shown in full lines will obviously reverse the direction of rotation of the countershaft from that imparted by the straight belt shown in dot and dash lines. Countershaft 42 drives the pulley 14 by means of a belt 46 (shown fragmentarily) and pulley 47. Many other mechanisms, some fully automatic, for effecting reversal of the drum may be used within the scope of the appended claims.

The apparatus may be used horizontally or vertically or in intermediate positions. If the apparatus is horizontally disposed an aperture in the cover plate 29, allows for inserting and removing the polishing agents. The aperture is closed by a removable cover plate 35.

Having fully described my invention, what I claim and desire to secure by Letters Patent is:

1. In a device for polishing articles, said device comprising a hollow drum mounted for rotation from a source of power, a carrier held stationary within the drum, said carrier adapted to carry the articles to be polished, a wall closing one end of the drum, a removable cover closing the other end, small pieces of material and polishing material placed within the drum, and a lining of resilient material applied to the inner periphery of the drum, and means for operating the drum intermittently in reverse directions.

2. In a device for polishing materials, said device comprising a hollow drum, a fixed wall closing one end of said drum, an axially disposed shaft rigidly secured to said wall, fixed bearings in which said shaft is journalled, means for driving said shaft in reverse directions, a removable cover closing the other end of the drum, an axial and rigidly supported arbor extending through said cover, a carrier disposed axially within the drum

and carried by said arbor, said carrier adapted to carry the articles required to be polished and small solid pieces of material and polishing material placed within the drum.

5. A process for polishing articles, consisting in mounting the articles on a carrier within a drum, together with a mixture of resilient material and abrasive material, and rotating the drum at a speed sufficient to cause a portion of said mixture to pack on the inner periphery of the drum by centrifugal force and in close proximity to the surface of said articles while other portions of said mixture pass between and in contact with said packed mixture and said articles, whereby to effect an abrasive polishing action thereof.

4. A process for polishing articles, consisting in mounting the articles on a carrier within a closed drum, placing a mixture of resilient material and polishing material within the drum, rotating the drum at a speed high enough to cause a portion of said mixture to pack on the inner periphery of the drum by centrifugal force and in close proximity to the surface of said articles while other portions of said mixture pass between and in contact with said packed mixture and said articles, whereby to polish said articles.

ERNEST GEORGE WHITEHEAD.
